(57) **CLAIM**

The ornamental design for a lighting frame, as shown and described.

DESCRIPTION

FIG. 1 is a front perspective view of an embodiment of a lighting frame in the present invention.

FIG. 2 is a rear perspective view thereof.

FIG. 3 is a front view thereof.

FIG. 4 is a rear view thereof.

FIG. 5 is a top view thereof.

FIG. 6 is a bottom view thereof.

FIG. 7 is a right side view thereof.

FIG. 8 is a left side view thereof.

FIG. 9 is a perspective view thereof in a folded position; and, FIG. 10 is a front perspective view thereof showing environment of use with a diffuser and a light panel attached with hook and loop fastener.

The broken lines shown in the drawings represent unclaimed portions of the design as well as environmental structure that forms no part of the claimed design.

1 Claim, 5 Drawing Sheets
